UNITED STATES PATENT OFFICE.

JAMES HARRY KEIGHLY McCOLLUM, OF TORONTO, CANADA.

AIR-VALVE.

SPECIFICATION forming part of Letters Patent No. 621,841, dated March 28, 1899.

Application filed April 7, 1898. Serial No. 676,793. (No model.)

To all whom it may concern:

Be it known that I, JAMES HARRY KEIGHLY McCOLLUM, electrician, of the city of Toronto, in the county of York, in the Province 5 of Ontario, Canada, have invented certain new and useful Improvements in Air-Valves, of which the following is a specification.

My invention relates to improvements in air-valves; and the object of the invention is 10 to devise a valve particularly adaptable for bicycles, which will be always absolutely air-tight except during the period that the air is being pumped through it and be so air-tight quite independently of the usual cap; and it 15 consists, essentially, of a valve comprising a suitable hollow casing with enlarged upper end, the lower end of the casing being provided with a tubular elasical covering, preferably of rubber, and the interior being provided with a hollow stem, with a head screwed 20 into the threaded upper interior portion of the casing and an inclosing cap provided with a suitable washer for closing the upper end of the stem and a screw-nut having a 25 central hole which fits over a stem on the end of the closing-cap, such cap being of less diameter than the portions of the hollow casing in which it fits and the screw-cap of the stem and screw-nut being provided with side- 30 notches arranged as hereinafter more particularly explained.

Figure 1 is a sectional perspective view of a valve constructed in accordance with my invention, showing it completely closed. Fig. 35 2 is a similar view showing the outer cap removed and the inner cap raised to permit of deflation of the tire or other air-space. Fig. 3 is a perspective view of the stem. Fig. 4 is a perspective view of the outer cap. Fig. 40 5 is a perspective view of the inner cap and screw-nut connected thereto.

In the drawings like letters of reference indicate corresponding parts in each figure.

A is the casing, which consists of the enlarged upper portion A', internally threaded at a, and the reduced lower portion A'', which is provided with a tubular covering B, of rubber or other suitable elastic material, which is suitably fastened to the outside of the portion A'' by thread or other suitable fastening, so as to make an air-tight connection between

the tube and the portion A''. The tube B preferably extends down below the bottom of the portion A'', as indicated.

C is the ordinary mushroom, which is secured on the reduced portion A'', as indicated. 55

D is a hollow stem provided with a head D', having a screw-thread d and side notches d'. The stem D when screwed down to its seat, as indicated in the drawings, projects 60 below the bottom of the portion A'', and as the stem is of less diameter than the interior hole a' a clear annular passage-way is provided from the upper threaded portion of the valve down to where the tube B presses upon 65 the stem. The notches d' permit of the passage of the air to the hole a' around the stem while the tire is being inflated, the unconfined narrowed portion of the tube B yielding to permit the entrance of air, but preventing its escape. 70

It will be noticed that the head D' has a reduced upper end d' of substantially the same diameter as the major portion of the stem.

E is a cap provided with a lower circular 75 recess e, having located therein a circular washer e'. The cap E is provided with an upwardly-extending stem e'', which extends through a screw-nut F. These portions are securely, though loosely, held together, the upper end of the stem e'' being pinched at f in its manufacture, so as to press it and enlarge it after such stem has been inserted into the hole e' of the nut, and thereby serves to retain the nut and cap together. A cross- 85 notch f' extends across the top of the nut F.

G is the outer cap, which is provided with a knurled enlarged central portion G', threaded lower end G'', and cylindrical upper end G', provided with projections g g. 90

Having now described the principal parts involved in my invention, I shall briefly describe the utility of my valve.

In the position in which the valve is shown in Fig. 1 it will be noticed that the washer 95 e of the cap E rests upon the top d' of the valve-stem D. It will therefore be seen that if the cap G is removed the stem will be still air-tight, the central hollow stem being closed and the rubber tube hugging closely the lower 100 end of the stem D. Consequently it does not matter in my valve whether the cap G is re-

moved or not; but in order to keep the dirt out it will be preferably used, as well as for the other purpose, which I shall now describe.

In order to deflate the valve-stem, the cap

- 5 G when removed may be turned upside down and the projections *g* inserted into the notch *f'* on each side of the stem *e*² of the cap E. By now turning the screw-nut F the cap E may be raised into the position shown in Fig. 2.
- 10 By so raising the cap there will be no rotary motion communicated to it, at least until it is entirely off its seat. It will thus be seen that there will be no tendency for the washer *e'*, which is preferably of rubber, to become
- 15 worn out, as would otherwise be the case if the cap E and nut F were integral. In lowering the cap E down into the position shown in Fig. 1 it will also be noticed that the washer *e'* will also be brought into direct
- 20 contact with the top *d*² of the hollow stem D, and this, too, without turning the cap or deleteriously affecting the washer. In the position in which the cap E is shown in Fig. 2 it will be clearly understood that the tire
- 25 will be readily deflated.

As it is of course very seldom necessary to deflate the tire, the stem D will be very seldom disturbed.

It will be noticed that I preferably reduce

- 30 the diameter of the lower end of the stem and provides substantially V-shaped annular rings, which I find in practice effectually prevents any retrocession of the air.

What I claim as my invention is—

- 35 1. An air-valve comprising the casing having an enlarged upper end internally threaded, the stem fitting therein and extending below the bottom of the casing, so as to leave a passage-way around it into the upper portion
- 40 of the casing, the elastical tube fitting the lower portion of the casing and hugging the bottom of the hollow stem, a suitable head attached to the top of the hollow stem provided with apertures and means for closing the top
- 45 of the hollow stem as and for the purpose specified.

- 2. An air-valve comprising the casing having an enlarged upper end internally threaded, the stem fitting therein and extending below the bottom of the casing, so as to leave a passage-way around it into the upper portion of the casing, the elastical tube fitting the lower portion of the casing and hugging the bottom of the hollow stem, a suitable head attached to the top of the hollow stem provided with apertures and an exterior thread on the head for securing it in position and a cap of less diameter than the interior of the casing provided with a circular bottom recess and
- 55 washer therein and a screw connection to the thread of the hollow casing and means for vertically adjusting the cap to and from the top of the hollow stem and suitable apertures in the cap circumferentially outside the washer
- 60 as and for the purpose specified.
- 65 3. In an air-valve, in combination the cas-

ing having an enlarged upper end internally threaded, the stem fitting therein and extending below the bottom of the casing, so as to leave a passage-way around it into the upper 70 portion of the casing, the elastical tube fitting the lower portion of the casing and hugging the bottom of the hollow stem, a suitable head attached to the top of the hollow stem provided with apertures and an exterior 75 thread on the head for securing it in position, a cap of less diameter than the interior of the casing provided with a circular bottom recess and washer therein and an upwardly-extending stem having an enlarged upper end, a 80 screw - nut having a central hole through which such stem extends and by which the cap and nut are connected together and side notches in the nut as and for the purpose specified. 85

4. In an air-valve, in combination the casing having an enlarged upper end internally threaded, the stem fitting therein and extending below the bottom of the casing, so as to leave a passage-way around it into the upper 90 portion of the casing, the elastical tube fitting the lower portion of the casing and hugging the bottom of the hollow stem, a suitable head attached to the top of the hollow stem provided with apertures and an exterior thread 95 on the head for securing it in position, a cap of less diameter than the interior of the casing provided with a circular bottom recess and washer therein and a screw connection to the thread of the hollow casing, means for vertically adjusting the cap to and from the top of the hollow stem and suitable apertures in the cap circumferentially outside the washers, a cross-notch at the top of the cap and the outer cap provided with a correspondingly-shaped projection to fit into the cross-notch of the cap as and for the purpose specified. 100

5. In an air-valve, in combination the casing having an enlarged upper end internally threaded, the stem fitting therein and extending below the bottom of the casing, so as to leave a passage-way around it into the upper portion of the casing, the elastical tube fitting the lower portion of the casing and hugging the bottom of the hollow stem, a suitable head attached to the top of the hollow stem provided with apertures and an exterior thread on the head for securing it in position, a cap of less diameter than the interior of the 110 casing provided with a circular bottom recess and washer therein, an upwardly-extending stem having an enlarged upper end, a screw-nut having a central hole through which such 115 stem extends and by which the cap and nut are connected together and side notches in the nut, a cross-notch in the nut and the outer cap provided with projections designed to fit into the notch on each side of the central stem of the cap as and for the purpose 120 specified. 125

6. An air-valve comprising the casing, the

stem fitting therein and extending below the bottom of the casing, so as to leave a passage-way around it into the upper portion of the casing and having the annular projections on the bottom of the hollow stem and means for closing the top of such stem as and for the purpose specified.

5 on the bottom of the hollow stem and means for closing the top of such stem as and for the purpose specified.
